UNITED STATES PATENT OFFICE.

EDWARD H. PHIPPS, OF NEW HAVEN, CONNECTICUT.

PUNCHING-MACHINE.

SPECIFICATION forming part of Letters Patent No. 340,817, dated April 27, 1886.

Application filed October 27, 1885. Serial No. 181,084. (No model.)

To all whom it may concern:

Be it known that I, EDWARD H. PHIPPS, of New Haven, in the county of New Haven, and in the State of Connecticut, have invented certain new and useful Improvements in Punching-Machines; and I do hereby declare that the following is a full, clear, and exact description thereof, reference being had to the accompanying drawings, in which—

10 Figure I shows a view in front elevation of my punching-machine; Fig. II, a plan view of the same; Fig. III, an end view of the same; Fig. IV, a detail view in elevation of the mechanism for driving the feed-rolls, and Fig. V a 15 vertical sectional view on line $x-x$ of Fig. I.

Letters of like name and kind refer to like parts in each of the figures.

The object of my invention is to provide an improved punching-machine; and to this end 20 my invention consists in the construction, arrangement, and combination of parts, as hereinafter specified, and more particularly pointed out in the claims.

My invention relates to that class of punching-machines in which it is desirable that the 25 punches should be kept continuously at work and the metal to be punched should be automatically fed up to and under the punches—as, for instance, in the case of machines for 30 punching rivet-holes in sheet-iron to be riveted into pipe, or for punching any shapes or blanks out of sheet-metal strips.

In the drawings, A designates the bed or 35 table of the machine, to be supported on suitable legs, as shown, or otherwise, as desired. Upon this bed, which has the longitudinal 40 opening A', with vertical sides, rest the two heads B C, containing and carrying the punching mechanism and devices. Of these, one, the head C, is preferably made stationary, being bolted or otherwise fastened to the bed. The punch carried by this head is, as shown, 45 on the inner side of the head, so as to be in position to punch the holes along the outer edge of a sheet fed through the machine.

The head B is movable along the bed, and has a portion, B', extending down and fitting between the inner sides of the longitudinal 50 opening A' in the bed, so as to hold the head most steadily and firmly in any position along the bed, and to guide it as it is moved along

the latter. Through this portion B' is tapped the adjusting-screw S, which extends centrally and longitudinally between the sides of the opening A', and at one end is journaled in a bearing, s, and at the other has an unthreaded shank or extension journaled in and extending through the end of the bed. Upon the outer end of this plain portion of the screw is the hand-wheel S', by which the screw can be rotated, as desired, to adjust the head B in either direction along the bed. The punch in this head is, as shown, on the side toward head C, so that both punches can be made to operate at the same time upon opposite edges of a sheet 65 of metal fed through the machine between the heads.

To operate the punches, I provide a longitudinal shaft, D, above the bed A, journaled at one end in a bearing, d, on a suitable stand, D', extending up from the bed end, and at the other in bearings $d'd'$ on the top of head C. The head B is also provided with bearings $d'd'$, through which the shaft passes and in which it is journaled. Such bearings are 75 adapted to slide freely along the shaft as the head is moved by the adjusting-screw.

Upon the journal-stud E, attached to the end of the bed A, is journaled the pulley H, to be driven by a band from any desired source of 80 power. Made rigid with this pulley is the gear I, which meshes with and drives the gear-wheel J on the end of shaft D, just beyond bearing d.

The bearings for the shaft on the heads B C are preferably made double, as shown, and upon the shaft between the two parts of the bearing on each head is the eccentric L for actuating the punches. These eccentrics are feathered or splined on the shaft, as shown, the shaft being provided with a longitudinal feather 90 or spline, l, so that while the eccentric operating the punch in head B is caused to revolve with the shaft it can move freely along the same with the head. Each eccentric is provided with an eccentric strap or sleeve, L', 95 formed with the arm L^2 , pivotally connected at its lower end with the block L^3 , carrying the punch l' , attached to it in any of the well-known ways desired.

The dies l^2 are keyed to and entirely supported by portions of the heads B and C, so that all strains due to the punching are en-

tirely taken up and held in the heads and not distributed throughout the machine, as in punching-machines as heretofore made.

To feed the sheet being punched along under the punches, so that the holes made will be at the desired distance apart, I provide the two pairs of feed-rolls M N and O P on opposite sides of the bed A. These rolls are at their ends journaled in blocks R R, held in the brackets K K on the bed, so as to be capable of vertical movement in the same. Above the upper block of each pair is a plate, K', fastened to the top of the bracket and extending across the opening therein, in which are held the journal-blocks. A screw, k, is tapped down through this plate, so as to limit with its lower end the amount of possible rise of the upper journal-block. On the journal shafts or axles of the rollers beyond the journal-blocks at one end are the meshing small gears m n o p, respectively, having their teeth made of such depth as to allow of movement of the upper rolls with reference to the lower ones, while the gears still remain in mesh.

25 On the shafts of the rollers N and P are the gear-wheels N' and P', respectively, of equal diameters, with which gears the gear-wheel R', journaled on the portion of the screw which projects beyond the bed end, as described. 30 The toothed wheel R² is made rigid with this wheel on the outer side thereof, and between wheel R² and the hand-wheel S' there is pivoted upon the shank or shaft of the screw S the arm T, carrying the pivoted double pawl 35 U, adapted as it is swung one way or the other to engage the teeth of the wheel R² on one side or the other of the arm, to drive the wheel R² in either direction, as desired. The outer side of the pawl is made wedge-shaped, with the 40 edge of the wedge substantially parallel to the axis of motion of the pawl and equidistant from the engaging ends of the pawl. In a suitable socket or recess in the arm T is the spring-pressed block or bolt t, bearing against the 45 outer side of the pawl. Attached to the pivot-shaft of the pawl is a thumb-wheel or head, N², by which the pawl can be turned, as desired.

With the construction just described, if the 50 pawl be turned to the middle point of its swing, as shown in Fig. 4, the block or bolt t, bearing against the edge of the wedge, does not tend to swing the pawl in either direction, but holds it with its teeth or engaging ends both 55 clear of the teeth of wheel R²; but if the pawl be swung in either direction from such position, the bolt, bearing upon one of the sides of the wedge, will keep the pawl swung in that direction, and will operate with its yielding 60 pressure to cause the pawl to engage the teeth on wheel R². The pawl can then be easily and quickly set to drive the wheel in either direction or to be disengaged entirely from it, so that the 65 arm T can be swung freely up and down without turning the wheel. When the pawl is set to engage the teeth of the wheel as the arm is

moved, the wheel will obviously be turned intermittently through a distance proportionate to the throw of the arm on its pivot. This intermittent rotation is imparted through the 70 connecting gearing described to the feed-rolls. The amount or extent of each partial revolution of the feed-rolls can then be regulated as desired to carry the sheet or blank between them the requisite distance by regulating the 75 throw of the pawl-carrying arm.

To actuate the arm from the same shaft which drives the punches, I provide on the shaft D the crank-wheel V, having a crank-pin, V', made adjustable diametrically across 80 the wheel in the well-known way. A connecting-rod, W, connects this crank-pin with a pin on the arm T. By adjusting the crank-pin upon the wheel the throw of the rod W, and also that of the pawl-arm, can be adjusted 85 as desired, to regulate the feed by the feed-rolls, as hereinbefore set forth.

As the blanks or sheets of metal must be moved or fed along under the punches at the intervals when the punches are not in the dies 90 or engaging the metal, the feed-rolls should begin to move at a time when the punches have made half their rise and should finish their movement before said punches have made more than half their descent—that is, the feed-rolls should complete their movement during 95 a half-revolution of shaft D. The crank-wheel V is therefore set upon the shaft so that the diameter of the wheel upon which the crank-pin is situated, and along which it is adjustable, as described, will be at right angles to the longer radii of the eccentrics L L on the shaft. With this construction and arrangement of the parts, the arm T can be made to begin and complete that part of its throw 100 which actuates the wheel R² through the pawl or ratchet U during that part of the rotation of the eccentrics which raises the punch-bearing blocks through the latter half of their ascent and lowers them through half of their 105 descent.

If it is desired to reverse the motion of the arm T with reference to the rotation of the shaft and motion of the eccentrics thereon, the crank-pin V' can be moved over to the opposite side of the center of the crank-wheel. The pawl U can then be turned to engage the wheel on the other stroke of the arm T, so as to rotate the feed-wheels in the opposite direction and at the proper times with reference to 110 the movements of the punches.

If desired, springs can be used to press down the journal-boxes of the upper feed-rolls, but I find that the weight of such rolls is sufficient to cause the rolls to take a firm enough hold 115 upon the metal sheet or blank. I have also found that it is unnecessary to roughen the surfaces of the rolls, though that can, of course, be done.

Any desired number of heads like head B 120 can be placed on bed A, connected with the shaft D, and adjusted by screw S in the same

manner as head B. The heads are all, as those shown in the drawings, to be formed with suitable tables or platforms, upon which the dies are keyed and supported, as described 5 hereinbefore.

Obviously the shaft D can be grooved and the eccentrics be provided with a feather entering the groove, or the opposite construction can be used.

10 I do not limit myself to any form or manner of connecting the eccentrics with the shaft to allow of their motion along it.

In using my machine, the crank-pin having been adjusted to give the proper amount of 15 movement to the feed-rolls each time through the connecting mechanism set forth, and the head B having been adjusted by screw S to bring it into such position that its punch will strike sheet or blank at the desired distance 20 from the edge thereof, the sheet or blank is placed upon table X with its edge against the guiding or gage pins x x, and its forward end is inserted between the feed-rolls on the front side of the machine. The machine is then put 25 in operation, and the sheet is fed by the rolls intermittently forward, being advanced after each punching just the right distance for the next hole to be made by the punches.

When the sheet or blank is engaged on both 30 sides of the machine and the punches thereof by the feed-rolls, it is fed forward most accurately and positively.

I do not claim herein or desire to cover by 35 my claims two pairs of feed-rolls, of which only one pair is driven directly by suitable driving mechanism, and the other pair is driven from the first pair by intermediate gearing.

Having thus described my invention, what I 40 claim is—

1. In combination with the bed and two or more heads supported thereon, the rotary shaft passing through suitable bearings on the heads, the punching mechanism supported entirely 45 upon the heads and driven by connection with the shaft, substantially as and for the purpose described.

2. In combination with a suitable supporting-bed, the fixed head on the bed, the rotary shaft journaled in bearings on such head, the 50 standard, and the bearing thereon for the end of the shaft, the movable head supported on the bed, the bearings for the shaft on the latter head, and suitable punching devices carried and entirely supported by the heads and 55 driven from the shaft, substantially as and for the purpose described.

3. In combination with a suitable bed, a head fixed thereon at or near one end, a standard at or near the other end, journal-bearings 60 for the shaft on the head and standard, a movable head supported on the bed, bearings on this head through which the shaft passes, suitable punching devices carried and supported entirely by the heads and driven from the 65 shaft, and an adjusting-screw engaging a portion of the movable head, substantially as and for the purpose described.

4. In a punching-machine, the stationary 70 punching-head, the movable punching-head, the adjusting-screw for the latter, and the pairs of feed-rolls on opposite sides of the heads, all in combination, substantially as and for the purpose described.

5. In combination with the toothed wheel 75 for driving the feed-rolls of a punching-machine through suitable connecting-gearing, the pivoted arm, the double pawl pivoted thereon, provided with a wedge-shaped projection on its back or outer side, the spring-bolt engaging such side of the pawl, the connecting-rod, the crank-disk, and the crank-pin thereon made adjustable diametrically across the disk, substantially as and for the purpose described. 80

In testimony that I claim the foregoing I have hereunto set my hand this 15th day of September, 1885. 85

E. H. PHIPPS.
